UNITED STATES PATENT OFFICE.

JOHN S. SKELLY, OF MONONGAHELA, PENNSYLVANIA, ASSIGNOR TO COMBUSTION ENGINEERING CORPORATION, OF NEW YORK, N. Y., A CORPORATION OF NEW YORK.

STOKER FURNACE.

Application filed January 18, 1920. Serial No. 351,187.

To all whom it may concern:

Be it known that I, JOHN S. SKELLY, a citizen of the United States, residing at Monongahela, county of Washington, State of Pennsylvania, have invented a certain new and useful Improvement in Stoker Furnaces, of which the following is a full, clear, and exact description.

My invention relates to stoker furnaces and has for its object to provide a front underfeed stoker in which fuel is fed to the grate with a substantially uniform thickness at all points; it further has for its object to provide a suitable pusher mechanism actuated by a shaft rotating slowly in one direction and free from crank arms or movable links.

One feature of my invention consists in the use of an inclined grate and a retort extending practically or substantially the full width of the grate, and means for underfeeding fuel from the front directly through said retort to the grate at all points along the front edge thereof; another feature consists in the use of internal cams for reciprocating the pushers.

The following is a description of an embodiment of my invention; reference being had to the accompanying drawings, in which,

Fig. 1 shows a horizontal sectional view on the line 1—1, Fig. 2;

Fig. 2 shows a vertical section on the line 2—2, Fig. 1, part of the side wall being removed;

Fig. 3 shows an enlarged detail of the means for reciprocating the pusher and grate bars, while

Fig. 4 shows a modification of the same; Figs. 5 and 6 are sectional details of grate bars of the stoker.

Fig. 7 shows on a reduced scale, a fragmentary plan view of portions of the two sets of grate bars and their supports and means for reciprocating alternate bars.

Referring more particularly to the drawings, 1 is the furnace setting carrying the stoker mechanism. 2 is a hopper for fuel discharging at its lower end into a passage 3, from whence it is forced by reciprocating pushers 4, 4 toward a set of inclined grate bars 5, 5', constituting the upper section of the grate, the upper ends of which are supported by the lower wall of the passage 3, while the lower ends are supported by a

wall 6. Below the section containing the grate bars 5, 5' is another set of grate bars 7, 7', constituting the lower section of the grate, which are preferably not inclined to the same extent as the bars 5, 5'. The upper ends of the bars 7, 7' are supported by a wall 8, while their lower ends are supported by a wall 9. In each of the two sections the alternate grate bars 5 and 7 are movable, the intermediate bars 5' and 7' being stationary after the manner shown in patent to W. R. Wood, No. 818,010 granted April 17, 1906. In order to move the movable bars, they are provided on their under sides with recesses 10 and 11 in which fit flanges upon rocker bars 12 and 13 respectively. These rocker bars extend half-way across each grate section, as shown, so that they can be independently actuated. To the outer ends of these rocker bars are connected lever arms 14 and 15, respectively. The lower end of each lever 14 is connected to the upper end of the corresponding lever 15 by a link 16. The lower ends of the levers 14 are also connected by links 17 to crank pins 18 respectively upon disks 19 rotated by gears 20 mounted upon shafts 19', there being two disks 19 and gears 20 located on opposite sides of the furnace and independently actuated as hereafter described.

Meshing with each gear 20 is a gear 21, these gears 21 being upon shafts 22 upon each of which shafts are secured two radially projecting members 23 each provided with an anti-friction roller 24. These radially projecting members 23 rotate within frames 25 each frame having abutments 26 and 27 facing in opposite directions. These abutments are on different sides of the vertical plane passing through the axis of the shafts 22.

The gears 21 are driven by any suitable means such as gears 28 meshing therewith so as to cause the shafts 22 and projections 23 to revolve slowly in a clockwise direction. As these members are revolved the anti-friction rollers 24 engage the abutments 27 to move the frames and pushers 4 connected therewith to the right (Fig. 2) feeding coal from the discharge of the hopper toward the stoker grate. A further movement of the shafts 22 causes the anti-friction rollers 23 to engage the abutments 26 causing the pushers 4 to move to the left so as to be in a position to force forward

more coal upon its next forward stroke. At the same time the revolution of the pins 18, acting through the links 17 and 16, causes the movable bars in the upper and lower 5 grate sections to reciprocate, the movable bars in the two sections moving in opposite directions.

The opening 3 extends the full width of the grate made up of the bars 5, 5' and the 10 pushers 4, 4' extend the full width of that opening except for a narrow supporting wall 4' which is located between adjacent sides of the pushers when necessary, depending upon the width of the pushers and their 15 number. The forward wall of the hopper 2 is provided with an opening through which the pushers 4 extend and substantially fill the same. The mouth of the hopper is of similar width, so that the pushers 4, 4' 20 feed fuel to all parts of the upper end of the grate. By these full width pushers the fuel is underfed with a substantially uniform thickness to all points along the upper end of the upper section. The portion 3' of 25 the opening, adjacent to the upper ends of the bars 5, 5', constitutes a retort for coal to be burned upon the grate.

In order to supply air to the upper grate section an air duct 29 is provided which supplies 30 air to the chamber 30 formed beneath the upper ends of the bars 5 by the wall 31. This causes air to pass through the inlet ports 5² of the tubular bars 5, 5' so as to be discharged into the chamber 32 between the 35 walls 6 and 31 through the outlet ports 5³ located adjacent to the lower ends of the bars. 30¹ is a damper for controlling this air. An air duct 30² supplies air to the chamber between the walls 6 and 8 for the 40 inlet ports 7² located at the upper ends of the bars 7, 7'. The air is discharged through outlet ports 7³ located at the lower ends of the bars 7, 7' into the chamber 33 formed by the walls 8 and 9, from whence it passes 45 upward between the bars 7, 7' of the lower section to the superimposed fuel. A damper 30³ controls this air. The air passing through the bars 5, 5' passes upward between those bars to the superimposed fuel 50 while the air which passes through the tubular bars 7, 7' passes upward between those bars. In this way the air to the two grate sections can be independently controlled.

The result of the operation of the apparatus above described is that coal is underfed slowly by the internal cam-operated pushers from the hopper directly through the retort to the upper grate section so as to be of uniform thickness throughout its 55 width and caused to move down the grate by the moving bars thereof to the lower section, where similar movements result in further progressive movement of the fuel at any desired slower rate. Primary combustion takes place upon the grate bars of 60

the upper section and the air passing through those grate bars is heated thereby. The complete combustion takes place on the lower section where by retarding the movement the partially burned fuel can be consolidated so as to prevent thin spots, the air passing through this consolidated fuel being regulated according to conditions. The retardation of the fuel on the lower bars is brought about by the regulation of 70 their movements, such regulation being obtainable on account of the possibility of adjusting the bars 16 and 17 relatively to the lever arms 14 and 15, holes in the lever arm being provided for that purpose, as shown 80 more clearly in Fig. 3.

In the construction shown there are two pushers 4 placed side by side and two frames 25 connected to each pusher, each frame actuated by a projection 23. There are also 85 two independent shafts 22 carrying the projections for the two separate pushers and the rocker bars 12 and 13 are divided at their centers to form two independent sections so that the pushers and the corresponding rocker bars can be driven at different speeds if desired.

34 is an ash grate mounted upon a shaft 35 which is actuated through a worm gear 95 36 by a worm 37.

The movable bars 7 are in line with the stationary bars 5' and the stationary bars 7' are in line with movable bars 5. This arrangement assists in maintaining an even flow of fuel over the lower grate section.

In the modification shown in Fig. 4 the frame 25' connected to the pusher 4² instead of having two internal abutments is provided with a series of such abutments 26' and 27' on the two opposing faces and the shaft is provided with a plurality of radial projections 23' constituting a segment of the gear wheel, having a plurality of teeth as distinguished from the single tooth of Fig. 3. The resulting motion is the same, except that in the construction of Fig. 4 greater movement is obtained for a rotating member of the same diameter.

As will be evident to those skilled in the art, my invention permits of various modifications without departing from the spirit thereof or the scope of the appended claims.

What I claim is:

1. An underfeed stoker furnace having, in combination, an inclined grate, a retort at the upper end of the grate extending substantially the full width of the grate and having an opening in its forward side substantially of the width of the grate, a narrow partition intermediate the ends of the retort having its rear end substantially in front of the forward end of the grate, a hopper connected with the opening in the retort, and closely adjacent reciprocating 120

- pushers arranged at opposite sides of the partition and each of substantially the width of the space between said partition and the adjacent outer side wall of said opening.
- 5 2. An underfeed stoker having, in combination, a fuel feeding grate comprising inclined grate bars, a retort at the upper end of said grate extending substantially the full width thereof and to a point below the upper ends of said grate bars, a hopper having an opening in its forward wall leading into and of substantially the width of said retort, pusher means substantially filling said opening in the forward wall of the hopper and composed of a plurality of closely adjacent sections, and means for reciprocating said sections independently of each other.
- 10 3. An underfeed stoker furnace having, in combination, a grate, a fuel retort ex-
- tending across the front end of said grate, a hopper having its lower end in communication with the forward end of said retort, fuel pushers mounted to slide in an opening in the lower end of the front wall of the hopper for feeding fuel into said retort, said pushers closing said opening and being guided by the walls thereof, and means for actuating said pushers comprising a plurality of frames carrying each pusher and located in front of the forward end of said opening and outside of the furnace, and rotating members extending through the frames, each of said frames having suitably arranged abutments, and each of said rotating members having suitable projecting means adapted to engage said abutments alternately so as to reciprocate said frame and pusher.

JOHN S. SKELLY.
